[57] CLAIM

The ornamental design for a solar space heater, as shown and described.

DESCRIPTION

FIG. 1 is a front perspective view of a solar space heater, showing our new design;

FIG. 2 is a top plan view thereof;

FIG. 3 is a bottom view thereof;

FIG. 4 is a left side elevational view, the right side being identical thereto;

FIG. 5 is an end elevational view, the opposite end being identical thereto.

FIG. 1

FIG. 2

FIG. 3

FIG. 4

FIG. 5
